PHONOGRAPH RECORD CABINET

Sylvan K. Ketterman, Chicago, Ill., assignor to
Gulbransen Company, Chicago, Ill., a corpora-
tion of Illinois

Application January 5, 1942, Serial No. 425,617

5 Claims. (Cl. 312—19)

My present invention relates to an improvement in a cabinet for conveniently storing a plurality of relatively thin disc-like members, such as phonograph records, and more particularly is concerned with means for selectively ejecting the records from the cabinet.

It is an object of my invention to provide a record cabinet comprising a plurality of partitions defining a plurality of record receiving spaces, and a simple and convenient record ejecting means adapted to be aligned with any selected record space and then actuated to eject therefrom the record therein. The record ejecting means preferably is of a character which may be readily shifted transversely of the several record spaces and when disposed in a selected position is actuatable rectilinearly in the plane of the selected record space to eject the desired record. Still more specifically means is provided to prevent actuation of the record ejecting means unless the same is in accurate alignment with a record space.

Other objects and advantages will appear from the detail description.

Now in order to acquaint those skilled in the art with the manner of constructing and operating a device in accordance with my invention, I shall describe in connection with the accompanying drawings a preferred embodiment of my invention.

In the drawings:

Figure 1 is a front elevational view of the record cabinet of my invention;

Figure 2 is a vertical sectional view taken substantially on line 2—2 of Figure 1, looking in the direction indicated by the arrows; and

Figure 3 is a fragmentary horizontal sectional view taken substantially on line 3—3 of Figure 2, looking in the direction indicated by the arrows.

Referring now to the drawings, the cabinet 4 comprises a top wall 5, a base or bottom wall 6, and a pair of end walls 7 which are suitably secured to the top and bottom walls. Suitable foot members 8 are secured one each to the outside surface and along the lower edge of the end walls 7. A plurality of partitions 9 are spaced longitudinally of the cabinet and the upper and lower edges of the several partitions seat in suitable grooves formed in the inner surfaces of the top member 5 and the base 6. The spaces between the partitions form record receiving spaces, and the partitions adjacent each end wall 7, together with the associated end walls, define end record receiving spaces. The partitions 9 pref-

erably are spaced slightly inwardly of the forward edges of the base 6 and top wall member 5 and extend inwardly substantially half the width of the cabinet. Preferably, the members comprising the cabinet and the partition 9 are made of wood and the parts are dimensioned so that various sizes of records may be accommodated.

A record rest bar 12 extends longitudinally of the cabinet at the rear thereof, and is secured to the rear edges of the end walls 7 by suitable wood screws 13. The inner face of the record rest bar 12 is provided with a pair of felt strips 15 and 16, the upper strip 15 providing a rest for records for example of 12" in diameter and the lower felt strip 16 providing a point of contact or support for records of a smaller dimension, for example of 10" in diameter. A record spacing bar 17 is suitably secured to the bottom edge of the member 12 and is provided with V-shaped projections 18 each adjacent pair of which defines a rearwardly converging slot for receiving the edge of a record disc. It will be clear from Figure 3 that a substantial portion of the respective records is disposed between two adjacent partitions and the rearward edges of the records are retained between adjacent projections 18 so that the records are held against warping.

A track 22 comprising a pair of opposed rabbed guide bars 22a and 22b is suitably secured to the under face of base 6 and extends longitudinally thereof adjacent the forward edge thereof. The front edge of the track 22 is provided with suitable indicia for identifying the record spaces of the cabinet. Track 22 slidably supports a record selecting and ejecting means 25, comprising a block member 26 having a T-shaped tongue portion 27 fitting in bars 22a and 22b and having sliding movement therein lengthwise of the cabinet. The block member 26 is recessed at 30 to slidably receive an arm 31 extending in a direction from front to back of the cabinet and projecting a short distance beyond the front of block 26. A base plate 32 is suitably secured to the base of block member 26. An operating knob 34 is secured to or formed integrally with the front end of the arm 31, adjacent the front of the cabinet, and a suitable indicating arrow 35 is provided on arm 31 for aligning the latter with any selected record space, indicated by the indicia on the track 22. Base 6 terminates a short distance from the back of the cabinet, and arm 31 extends rearward a short distance beyond base 6, as shown in Figure

2. A supporting block 36 is secured on the upper face of arm 31 and projects rearward therebeyond, with its rearward portion slotted vertically. A record ejecting lever 37 is pivotally mounted in the slot of block 36, on a pin 39 which extends through the arms 38 of the slotted portion thereof. A block 40 is secured to the under face of the arm 31 adjacent the rearward end thereof, and provides a stop limiting clockwise movement of the arm 37 about the pin 39, as viewed in Figure 2.

A torsion wire spring 41 has one arm secured in lever 37 above the pivot 39 and the other arm of spring 41 bears in a groove in the upper face of block 34. Spring 41 normally holds arm 37 in its rearward position, with its lower end in contact with the beveled rearward end of block 40, as shown in Figure 2. A fulcrum bar 45 extends longitudinally of the cabinet, at the rear and adjacent the lower edge thereof, and above the horizontal plane of the pivot pin 39.

The lever 37 is normally spaced from the fulcrum bar 45 to avoid friction between the lever and the bar to facilitate alignment of the ejecting means with a selected record space.

A register bar 47 extends longitudinally of the cabinet and is suitably secured to the lower surface of the base 6 intermediate the front and rear edges of the plate, and is provided in its under face with a plurality of slots 48 respectively lying in the vertical planes of the record spaces. A tongue 49 is suitably secured to the upper surface of the arm 31 and is adapted to have sliding engagement in the corresponding slots 48 of the bar 47 when the record ejecting means 25 is positioned in alignment with one of the several record spaces. A tension spring 50 is secured at one end to the plate member 32 and at its other end to the arm member 31. A pair of stop pins 52 are secured in and project downwardly from arm 31 and are disposed to contact the inner edge of plate member 32 so as to limit the outward movement of arm 31 to its position shown in Figure 2.

Now, it will be seen that any desired record may be ejected by grasping the knob 34 and sliding the ejecting means 25 to position the arrow 35 in alignment with the desired record space as indicated by the indicia on the edge of track 22. After this selection has been made the knob 34 is pressed inwardly moving arm 31 rearwardly in opposition to spring 50 until the ejecting lever 37 contacts bar 45, then in the continued rearward movement of bar 31, lever 37 pivots upon fulcrum bar 45 and is swung forwardly in the vertical plane of the record space to eject the record therein. In this manner movement is imparted to the ejecting lever 37 before it contacts a record disc to aid in overcoming the inertia of the record disc. Preferably, the base member 6 is inclined downward rearwardly of the cabinet so that the records are normally retained in the cabinet by gravity. The forward position of the record ejecting arm 31 is indicated in dotted lines in Figure 2. After the selected record has been ejected, the knob 24 is released and the spring 50 returns the arm member 31 to its normal position shown in full lines. The spring 41 then returns the record ejecting lever 37 to its normal position shown in full lines in Figure 2. The inner surface of each of the end walls 7 is recessed at 55 to permit operation of lever 37 when the record ejecting means 25 is positioned in alignment with the end record spaces of the cabinet.

It will be observed that unless the record ejector lever 37 is positioned in accurate alignment with a record space, the tongue 49 will not be in alignment with the corresponding groove 48 of the register bar 47 and the device cannot be operated. That assures that the lever 37 will contact the edge of the record, and guards against injury to the record, such as would be caused by lever 37 grazing or scraping along a face of the record.

It will be understood that all of the elements described with the exception of the springs 41 and 50 and ancillary assembling means such as wood screws and the like may all be made of wood or other suitable non-metal material.

While I have described what I consider to be the preferred embodiment of my invention, it will be understood that various modifications and rearrangements may be made without departing from the spirit and scope of the present invention.

I claim:

1. A phonograph record cabinet comprising a base inclined downwardly from the front of said cabinet, a plurality of vertical partitions between the base and the top of said cabinet spaced longitudinally thereof to define a plurality of record receiving spaces, a track extending longitudinally of said cabinet at the front thereof beneath said base, a fulcrum bar extending longitudinally of said cabinet at the rear thereof, record ejecting means slidably mounted on said track for selective alignment with any of said record spaces, said record ejecting means comprising an arm slidable rectilinearly and substantially at right angles to said track, a record ejecting lever pivotally connected to said arm and actuatable thereby into contact with said fulcrum bar and in a vertical plane forwardly within said cabinet, and means for preventing actuation of said arm member when said record ejecting means is not in alignment with a record space.

2. A phonograph record cabinet comprising a base inclined downwardly from the front of said cabinet, a plurality of vertical partitions between the base and top of said cabinet and spaced longitudinally thereof to define a plurality of record receiving spaces, said partitions terminating intermediate the front and rear of said cabinet, a track extending longitudinally of said cabinet at the front thereof beneath said base, a fulcrum bar extending longitudinally of said cabinet at the rear thereof, a record rest bar extending parallel to and disposed above said fulcrum bar, said record bar comprising a plurality of projections defining a plurality of slots one each lying in the vertical plane of each of said record spaces, record ejecting means mounted for sliding movement upon said track for selective alignment with any of said record spaces, said record ejecting means comprising an arm slidable rectilinearly inwardly of said cabinet at substantially right angles to said track member, and a record ejecting lever pivotally connected to said arm and actuatable thereby into contact with said fulcrum bar and in a vertical plane forwardly within said cabinet, a guide bar having a plurality of slots one for each of said record spaces lying in the vertical planes of the latter, respectively, and a tongue carried by said arm adapted to have sliding engagement with the associated slot of each record space whereby said arm member is actuatable only when in alignment with a record space.

3. A phonograph record cabinet comprising a

plurality of vertical partitions spaced longitudinally of said cabinet defining a plurality of spaces for receiving disc records, a fulcrum bar extending longitudinally of said cabinet at the rear thereof, a track extending longitudinally of the cabinet at the front thereof, a block slidable longitudinally of said cabinet on said track, an arm slidably mounted in said block at right angles to said track, one end of said arm being disposed adjacent the front of said cabinet and the other end being disposed at the rear of the cabinet, a record ejecting lever connected to said arm adjacent the rear end thereof for pivotal movement in a vertical plane, said block being positionable upon said track for selectively aligning said lever with any of said record spaces, and a stop member carried by said arm for limiting rearward pivotal movement of said lever, said fulcrum bar being arranged so that when said arm member is in its forwardmost position with respect to the cabinet, said lever is out of contact with said fulcrum bar, said arm being slidable toward the rear of said cabinet to position said lever in contact with said fulcrum bar and thereafter cause said lever to pivot thereupon for movement forwardly in a vertical plane within said cabinet.

4. A phonograph record cabinet comprising a base inclined downwardly from the front of said cabinet, a plurality of vertical partitions spaced longitudinally of said cabinet defining a plurality of spaces for receiving disc records, a fulcrum bar extending longitudinally of said cabinet at the rear thereof, a track extending longitudinally of said cabinet at the front thereof beneath said base, a block slidable longitudinally of said cabinet on said track, an arm slidably mounted in said block at right angles to said track, one end of said arm being disposed adjacent the front of said cabinet and the other end being disposed at the rear of said cabinet, a record ejecting lever pivotally connected to said arm adjacent the rear end thereof, said block member being positionable upon said track for selectively aligning said lever with any of said record spaces, a stop member carried by said arm at the rear end thereof, a first spring means normally retaining said lever in contact with said stop member, said fulcrum bar being arranged so that said lever is out of

- contact therewith in the normal position of said first spring means, stop means for limiting forward movement of said arm, and second spring means normally retaining said arm in its forward position, said arm being slidable toward the rear of said cabinet to position said lever in contact with said fulcrum bar and thereafter causing said lever to pivot thereupon for movement forwardly in a vertical plane within said cabinet.
5. A phonograph record cabinet comprising a base inclined downwardly from the front of said cabinet, a plurality of vertical partitions spaced longitudinally of said cabinet defining a plurality of spaces for receiving disc records, a fulcrum bar extending longitudinally of said cabinet at the rear thereof, a track extending longitudinally of said cabinet at the front thereof beneath said base, a block slidable longitudinally of said cabinet on said track, an arm slidably mounted in said block at right angles to said track, one end of said arm being disposed adjacent the front of said cabinet and the other end being disposed at the rear of said cabinet, a record ejecting lever pivotally connected to said arm adjacent the rear end thereof, said block member being positionable upon said track for selectively aligning said lever with any of said record spaces, a stop member carried by said arm at the rear end thereof, a first spring means normally retaining said lever in contact with said stop member, said fulcrum bar being arranged so that said lever is out of contact therewith in the normal position of said first spring means, stop means for limiting forward movement of said arm, second spring means normally retaining said arm in its forward position, said arm being slidable toward the rear of said cabinet to position said lever in contact with said fulcrum bar and thereafter causing said lever to pivot thereupon for movement forwardly in a vertical plane within said cabinet, and a guide member having a plurality of slots one for each of said record spaces lying in the vertical planes of the latter, respectively, and a tongue carried by said arm adapted to have sliding engagement with the associated slot of each record space whereby said arm member is actuatable only when in alignment with a record space.

SYLVAN K. KETTERMAN.
